UNITED STATES PATENT OFFICE.

JOHN HATHAWAY WILSON, OF MINNEAPOLIS, MINNESOTA, ASSIGNOR TO WILSON BROTHERS, OF MINNEAPOLIS, MINNESOTA, A FIRM COMPOSED OF THOMAS B. AND JOHN H. WILSON.

DESIGN FOR A SERVICE-EASEL.

53,059.

Specification for Design.

Patented Mar. 4, 1919.

Application filed June 15, 1918. Serial No. 240,246. Term of patent 7 years.

To all whom it may concern:

Be it known that I, JOHN H. WILSON, a citizen of the United States, residing at Minneapolis, in the county of Hennepin and State of Minnesota, have invented a new, original, and ornamental Design for a Service-Easel, of which the following is a specification, reference being had to the accompanying drawing, forming part thereof.

Figure 1 is a front elevation of a service easel, embodying my new design;

Fig. 2 is a rear elevation; and Fig. 3 is a side elevation.

Copies of this patent may be obtained for five cents each, by addressing the "Commissioner of Patents, Washington, D. C."

I claim:

The ornamental design for a service easel, substantially as shown.

In testimony that I claim the foregoing as my own, I have hereto affixed my signature in the presence of two witnesses.

JOHN HATHAWAY WILSON.
